RECALL VOTING APPARATUS FOR VOTING MACHINE

Ira G. Laws, Tulsa, Okla., assignor to Seismograph Service Corporation, Tulsa, Okla., a corporation of Delaware

Filed Nov. 9, 1961, Ser. No. 151,279
24 Claims. (Cl. 235—54)

The present invention relates generally to recall voting apparatus for use with voting machines of the type described and claimed in copending U.S. applications Serial Nos. 120,250 and 120,281, both filed on June 28, 1961, and both assigned to the same assignee as the present invention.

In voting machines of the type disclosed in the two copending applications referred to above, the voter's selections are made by manually sliding one or more voting keys or selectors from a neutral position to a voting or selecting position. Certain jurisdictions, for example, the State of California, require that the voting machine be equipped with recall voting facilities wherein the voter must first vote either "Yes" or "No" on the recall question before he is permitted to exercise a "further choice." To satisfy these requirements, it is necessary to interlock the sliding keys so that the key by which the "further choice" is to be made cannot be moved unless the "recall" key is first moved from its neutral position to either the "Yes" or "No" position of the recall question. Moreover, provision must also be made for preventing return of the "recall" key to the neutral position after the "further choice" key has been moved since, in the absence of such a provision, the voter could defeat the purpose of the interlock. The present invention, therefore, has for its principal object the provision of recall voting apparatus for meeting all of these requirements.

The invention has for another object the provision of simple, inexpensive structure which may be attached to a voting machine of the type described above to interlock the voting keys so that the "further choice" key cannot be moved unless the "recall" key has first been moved from its neutral position to a selecting position.

The invention has for a further object the provision of recall voting apparatus of the character described above and including structure effective when both the "recall" and "further choice" keys have been moved to selecting positions for positively preventing return of the "recall" key to its neutral position as long as the "further choice" key remains in a selecting position.

A further object of the invention is to provide recall voting structure of the character previously indicated which may be readily and conveniently added to or removed from the voting machine at different desired positions on the interior of the voting panel to program the machine for an election.

Another object of the invention is to provide a simple, compact recall voting structure which may be assembled on voting machines of the type described in the copending applications referred to above without requiring major reconstruction or redesign of these machines and without requiring alteration of the voting keys or selectors.

The foregoing and other objects are realized, in accordance with the present invention, by providing a novel interlock bar for use on voting machines of the type described in the above-identified copending applications Serial Nos. 120,250 and 120,281. Any number of such interlock bars may be employed depending upon the number of recall questions to be presented to the voter but, since all such bars are identical, only one will be considered in detail in the present application. To facil-

2

itate assembly of the bar, one or more of the columns carrying the sliding voting keys or selectors are provided with spaced apart, tapped openings for receiving a screw or pin pivotally supporting the recall bar. As is described in detail in the copending applications each column supports an elongated strip carrying a plurality of spaced apart stops for limiting the movement of the selectors or keys each of which is slideable from a neutral position adjacent one of the stops to one or more selecting positions indicating the voter's choice. In a recall voting proposition, a "recall" key is provided for movement from the neutral position to either a "Yes" selecting position or a "No" selecting position and, in addition, a "further choice" key is provided for movement from a neutral position to any one of a number of selecting positions, the latter number depending, of course, upon the number of "further choices" offered to the voter.

The recall bar of the present invention may be pivoted from a selector locking position to a selector releasing position but, with both the "recall" and "further choice" keys in their neutral positions the bar is located in its selector locking position where a first selector engaging portion thereon engages the "recall" key and a second selector engaging portion engages the "further choice" key. The second portion cooperates with one of the office stops to hold the "further choice" key in neutral position and to positively prevent movement of this key as long as the bar remains in its selector locking position. The bar is recessed adjacent the first selector engaging portion so that movement of the "recall" key from its neutral position to either its "Yes" selecting position or its "No" selecting position releases the bar for pivotal movement. When the "further choice" key is manually moved from its neutral position, it engages a camming surface on the recall bar and pivots the bar from its selector locking position to its selector releasing position. The "further choice" key may be manually moved to any desired one of the "further choice" selecting positions. When the "further choice" key is moved from its neutral position, it blocks the recall bar to prevent the latter from pivoting back to the selector locking position. With the recall bar held in its selector releasing position, the "recall" key is blocked by the bar so that this key cannot be restored to its neutral position, thus preventing the voter from defeating the purpose of the recall vote interlock. Of course, until the vote is cast by operating the "Vote" switch in the manner described in the copending applications, the voter may change his mind by returning the "further choice" key to neutral thus again permitting movement of the "recall" key. The "recall" and "further choice" keys may be manipulated in the manner described until the voter is completely satisfied with his choices whereupon the "Vote" switch may be operated to cast the vote.

The invention, both as to its organization and manner of operation together with further objects and advantages thereof, will best be understood by reference to the following detailed description taken in conjunction with the accompanying drawings wherein:

FIG. 1 is a fragmentary, front elevational view showing a portion of the front panel of the voting machine including a column programmed for the recall voting proposition;

FIG. 2 is an enlarged, fragmentary, sectional view taken along a line substantially corresponding to the line 2—2 in FIG. 1;

FIG. 3 is a fragmentary, sectional view taken along a line directly corresponding to the line 3—3 in FIG. 2 assuming that the latter shows the entire front panel construction;

FIG. 4 is a fragmentary view looking in the direction

of the arrow pointed lines 4—4 in FIG. 3 and shows the recall voting bar in its selector locking position; and

FIG. 5 is a view similar to FIG. 4 but shows the recall voting bar in its selector releasing position.

Referring now to the drawings and first to FIG. 1, a fragmentary portion of a voting machine 20 is there shown which is generally similar to the voting machine described and claimed in the above-identified application Serial No. 120,281. This voting machine comprises a substantially enclosed housing 21 formed by a number of panels locked together in any suitable manner as, for example, in the manner described in detail and claimed in copending application Serial No. 120,249, filed June 28, 1961, and assigned to the same assignee as the present invention. The housing 21 defines an upper generally vertically extending voting panel section identified by the reference numeral 22 and a lower power supply section 23 extending forwardly from the upper section to form a relatively low shelf 24. The upper section 22 includes a front face or voting panel 25 made up of a plurality of side-by-side vertically extending columns 25a, 25b, etc. Any desired number of such columns may be provided and each comprises an elongated member preferably formed of an extruded material such as aluminum. As is described in detail in the above-identified copending application Serial No. 120,281 and as is shown in FIG. 3 of the drawings, the extrusion is such that each column comprises a central body portion 26 having an inwardly extending longitudinal rib 27 adjacent a curved spring receiving region 28 lying alongside the rib 27 and extending lengthwise of the column. A relative thick edge portion 29 extends longitudinally along one side of the body portion 26 while a transversely and longitudinally extending leg 30 is formed at the other side. A flange 31 extends along the entire length of the column at the rearwardly disposed end of the leg 30. A pair of elongated slots 32 and 33 respectively formed in the edge portion 29 and in the leg 30 receive the opposed side edges of an elongated candidate strip 34 containing on its outer, exposed face a list of the offices or propositions to be decided by the voter. Thus, for example, if the election is a national election, this strip may contain an office title such as "Present" and therebeneath may appear the different candidates competing for this office. The office title and the candidates for the office will be referred to hereafter as an office group but it should be understood that this term may also refer to propositions on which a "Yes" or "No" answer is required as, for example, on bond issues, constitutional amendments, and the like. Each of the candidate positions or voting positions in each office group will be referred to hereinafter as a selecting position. The recesses 32 and 33 may also accommodate the opposed side edges of a transparent cover 38 for the purpose of preventing the candidate strip from being marked or damaged by the voter. The strip 38 is formed of sufficiently rigid material such as plastic to prevent its removal from the slots 32 and 33 by squeezing it toward the center from the two side edges.

A groove 39 is provided in the rear face of the body portion 26 to receive an elongated strip 40 having a series of spaced openings 40a (FIG. 2) therein to accommodate office stops or pins 41 which divide the different office groups of each column. Each office stop comprises a pin having a stem extending through one of the openings 40a and protruding outwardly beyond the strip and rearwardly of the front face of the column. An enlarged, rectangularly shaped, flat head 42 on each office stop pin seats within a groove or slot 43 formed in the body portion 26 adjacent the groove 39. The strip 40 may be provided with numerals or other indicia to identify the different openings 40a in order to facilitate insertion of the office stops in proper positions along the strip during programming of the voting machine in a manner described in detail in the copending application Serial No. 120,281 referred to above.

The edge portion 29 of the body member 26 is provided with an elongated longitudinally extending guide rail 44 lying adjacent a pair of grooves 45 and 46 for accommodating one or more voting keys or selectors 48 which are slideable along the columns to permit the voter to make his selections. In addition, each column is provided with a groove or slot 49 opening to the rear of the column for accommodating a second, perforated, elongated strip 50 carrying a plurality of detent release pins 51 located at spaced positions therealong for a purpose which will be evident in view of the above-identified application Serial No. 120,281.

To consider the operation of the recall voting facilities of the present invention, let it be assumed that the column 25b is programmed to present the recall voting proposition and that, a consequence, this column is divided into two office groups, namely, an office group in which the voter must vote either "Yes" or "No" on the recall voting question and a second office group in which the voter must choose between candidates A, B, C, D, E, F and G. Let it further be assumed that the voter is entitled to vote for only one of the latter seven candidates. Thus, under conditions, the candidate strip 34 inserted into the slots 32 and 33 will contain a first office title 34a presenting the recall question. For example, this title could be "Shall Mayor Smith be Recalled?". Immediately below the recall question title will appear the two alternatives "Yes" or "No" presented for the voter's choice in deciding the recall question. These two selecting positions are respectively labeled "Yes" and "No" on the candidate strip. Immediately below the selecting position labeled "No" will appear the "further choice" proposition which may contain a suitable title such as "Who Shall Replace Mayor Smith?". This "further choice" office title is identified by the reference numeral 34b in the drawings and immediately below this office title there appear the seven selecting positions respectively listing the candidates A, B, C, D, E, F and G.

As is shown in FIGS. 2, 4 and 5 of the drawings, an office stop 41a is inserted within an appropriate opening 40a in the strip 40 immediately above the recall question title 34a and a second stop 41b is inserted immediately above the "further choice" office group title 34b and just below the "No" selecting position of the "recall" office group. An additional office stop 41c is placed immediately below the selecting position containing the name of the candidate G in the "further choice" office group. The "recall" voting key used by the voter in deciding the recall vote question is identified by the reference numeral 48a and is adapted to slide along the column 25b between the office stops 41a and 41b while the "further choice" voting key or selector is identified by the numeral 48b and is adapted to slide along the column between the office stops 41b and 41c. The keys 48a and 48b obviously cannot pass the stops defining their office groups. When the voting keys 48a and 48b are respectively located against the office stops 41a and 41b, they are in their neutral positions. The key 48a is adapted to be moved from its neutral position to either of the selecting positions provided for the recall question whereupon it may be released to rest in the selecting position chosen. In similar manner, the "further choice" voting key 48b may be moved from its neutral position to a position adjacent any one of the seven candidates A, B, C, D, E, F or G. Since the voter is provided with only one key for each office group, he may, of course, select only one of the selecting positions within this group and, for this reason, it is not necessary to provide elaborate interlocks for preventing multiple voting in each office group. The number of selecting positions available in each of the columns is, of course, determined solely by the height of the column and the space occupied by each position. Obviously, any suitable number of selecting positions may be provided but in one form of the present invention thirty such positions were used although to simplify the

illustration a much smaller number has been shown in FIG. 1

As is shown in FIGS. 3 and 4 of the drawings, the voting keys are held in their neutral and selecting positions by detent means 53 associated with each column. This detent means preferably takes the form of a plurality of detent springs located one above the other within a longitudinally extending channel 52 formed in the rib 27 with each detent spring being secured within the channel by a bent, somewhat J-shaped resilient end portion 54 which snaps into the channel 52 and holds the detent spring firmly in position. The detent springs are closely packed within the channel 52 and extend along its entire length to prevent their movement longitudinally of the column. Each detent spring includes a laterally extending curved detent finger 55 extending outwardly from the J-shaped end portion 54 with each finger carrying at its outer end a key engaging portion 56. The curved detent finger 55 lies along the curved portion 28 of the column to provide a rigid backing for each detent spring. As is best shown in FIGS. 3 and 4, each of the key engaging portions 56 is bent to form a key holding notch 57 between adjacent keys in the column. To this end, each detent finger extends outwardly from the J-shaped end portion 54 for a distance such that its key engaging portion 56 is disposed in the path of sliding movement of the voting keys along its column. The detent fingers are normally flexed or biased to occupy the positions shown in FIG. 3 but when the voting key slides along the column to move over a detent finger, the finger is flexed rearwardly of the front panel or downwardly as viewed in FIG. 3. If the key is stopped either at a selecting position or at a neutral position, it seats within one of the key holding notches 57 and is thus resiliently held at the selected position with the adjacent detent springs holding the key being disposed in their non-flexed positions. To provide a detent for each neutral and selecting position on the voting panel, the J-shaped end portion is of such height that the detent fingers are vertically spaced apart to form notches 57 which are separated by a distance corresponding to the width of one of the selecting positions and the detent springs 53 are so oriented with respect to the stop receiving openings 40a in the strip 40 that when a voting key is in the neutral position seated against an office stop 41, it is also seated within a notch 57.

Turning now to the construction of the voting key 48 and referring particularly to FIGS. 3 and 4 of the drawings, it will be observed that this key comprises a generally rectangularly shaped body member having a pointer 59a thereon extending laterally to overlie the edge portion 29 of the column and to point to the different selecting positions and office titles spaced along the candidate strip 34 carried by that column. The guide rail 44 of the column extends loosely through a channel 58 formed in the key and, in addition, the key is provided with ribs extending toward each other and respectively seated within the grooves 45 and 46 to permit sliding movement of the key along the column but, at the same time, to prohibit removal of the key by the voter. A finger grip 59 extends forwardly from the pointer 59a to facilitate manipulation of the key by the voter from the exterior of the voting machine. A slot or channel 60 formed in one side of the key receives the flange 31 of the adjacent column but this slot is considerably wider than the thickness of the flange for a purpose which will become evident as the description proceeds. The flange 31 prevents tampering with the voting machine by insertion of a tool or other object through the slot formed between adjacent columns. The rearward portion of the voting key 48 is provided with a curved detent engaging region 61 shaped to seat snugly within the notches 57 and also to flex the detent fingers 53 during movement of the voting key along the column. The rearward portion of the key is also provided with a tooth 64 and with a curved surface portion 65 for purposes which will be evident in

view of the above-identified copending application Serial No. 120,281. Thus, the tooth 64 cooperates with the key restoring mechanism to release the detent during the restoration of the voting keys to their neutral positions while the surface portion 65 engages the counter actuating mechanism to record the voter's choices. To this end, the voting machine is preferably provided with a series of counters (not shown) extending along the rear of the machine and spaced from the columns 25a, 25b, etc. A scanning mechanism which is not shown in the drawings but which is described in detail in the copending application Serial No. 120,281 is moved in a first vote sensing direction to actuate the counters associated with those voting keys which have been moved to a selecting position in order to register the voter's choices. After the vote sensing sweep has been completed, the scanning mechanism is conditioned for the key restoring sweep during which the voting keys are restored to their neutral positions. The scanning mechanism is driven by a suitable drive mechanism a portion of which is shown in broken lines in FIG. 1 as is indicated at 68. A curtain 66 is driven by the scanning mechanism to cover the front panel of the voting machine after the vote sensing sweep has been completed and this curtain is raised during the key restoring sweep in a manner which is also described in detail in the copending application Serial No. 120,281. After the scanning mechanism has completed its vote sensing sweep, the curtain 66 completely covers the front panel 25 of the voting machine and the curtain remains in this position when the next voter approaches the machine, thus preserving the secrecy of the ballot. At the beginning of the next voting operation, the scanning mechanism makes its key restoring sweep to return all of the voting keys 48 to their neutral position and, at the same time, to raise the curtain 66 to uncover the front panel 25 so that the voter may make his selections.

In accordance with the present invention, means are provided interlocking the voting keys or selectors 48a and 48b in such manner that the voting key 48b cannot be moved from its neutral position unless the selector 48a has first been moved either to the "Yes" or "No" position within the recall office group and, in addition, the interlocking means further includes structure for preventing return movement of the "recall" voting key 48a to the neutral position after the "further choice" voting key 48b has been moved to one of the seven selecting positions within its office group. This interlock means is identified generally by the reference numeral 70 in FIGS. 2, 3, 4 and 5 and comprises an elongated bar 71 extending along one side of the column 25b containing the recall vote proposition. The bar 71 is of sufficient length to span both the office group under the candidate title 34a and the "further choice" group under the candidate title 34b. More specifically, the recall voting bar 71 is mounted for pivotal movement upon the flange 31 formed on the column 25a adjacent to the column 25b containing the recall vote proposition. The bar 71 has a thickness such that it fits loosely within the channel 60 formed in the voting keys mounted on the column 25b without interfering with the movement of the keys along the column. Means are also provided for pivotally mounting the bar at different spaced apart positions with respect to the column 25b to permit programming the voting machine for an election in such manner that the recall voting proposition can be set up at a desired position along the column. This pivotal mounting means comprises a pivot pin or screw 72 extending through an opening in the bar 71 and threaded or otherwise secured within any desired one of a series of vertically spaced, tapped apertures 73 formed in the flange 31. One such aperture 73 is provided for each selecting position on the column and through selection of the proper aperture to receive the pivot pin 72, the bar 71 may be mounted at any desired position along the column.

The bar 71 may be pivoted from a selector locking

position shown in FIG. 4 to a selector releasing position shown in FIG. 5. When the bar is in its selector locking position both of the voting keys 48a and 48b are in their neutral positions and, at this time, the "recall" voting key 48a engages a selector engaging portion 74 located at the upper side edge of the bar 71 in order to prevent the bar from being pivoted to the selector releasing position. With the bar 71 in the selector locking position shown in FIG. 4, the "further choice" voting key 48b is locked in its neutral position between the office stop pin 41b and a locking shoulder 75 formed by a recessed portion 76 extending along one side edge near the upper end of the bar 71. The recessed portion 76 forms a second shoulder 77 which performs a function to be described hereinafter. Thus, with the recall voting bar 71 in the selector locking position, the "further choice" voting key 48b cannot be moved from its neutral position and the bar 71 cannot be moved from the selector releasing position as long as the voting key 48a remains in its neutral position. Assuming that the voter decides to exercise a choice on the recall vote question by moving the "recall" voting key 48a from the neutral position to one of the "Yes" or "No" selecting positions, for example, to the "Yes" position as shown in FIG. 5, the "recall" voting key 48a will be moved out of engagement with the edge portion 74, thus releasing the bar 71 for pivotal movement about the pin 72. Obviously, movement of the "recall" voting key 48a to the "No" selecting position will also release the bar 71. After the voting key 48a has been moved to one of the two "Yes" or "No" selecting positions, the "further choice" voting key 48b may be moved from its neutral position to any one of the seven selecting positions below the office title 34b. This movement causes the voting key to ride along a camming surface formed by the shoulder 75 so that the bar 71 is pivoted from the selector locking position shown in FIG. 4 in a counterclockwise direction about the pin 72 to the selector releasing position shown in FIG. 5. Obviously, the voting key 48b may be moved to any one of the seven selecting positions in the "further choice" office group but in any one of these positions the side edge 78 of the recall bar 71 engages the inner face of the channel 60 to prevent return movement of the recall voting bar 71 to the selector locking position shown in FIG. 4. The recall voting bar 71 is, therefore, held in the selector releasing position shown in FIG. 5 wherein the shoulder 77 blocks movement of the voting key 48a back to the neutral position. Thus, the voter cannot defeat the purpose of the recall voting interlock by moving the voting key 48b to a position adjacent one of the candidate listings in the "further choice" office group and by then returning the key 48a to the neutral position. The voter can, of course, change his mind as to whether he desires to vote "Yes" or "No" on the recall voting question since the shoulder 77 merely prevents return of the "recall" voting key 48a to the neutral position. Moreover, at any time prior to actuation of the Vote switch (not shown) to begin the vote sensing sweep of the scanning mechanism the voter may alter his vote on the recall question by returning the key 48b to the neutral position to release the bar 71 for return pivot movement to the selector locking position in which case the recall voting key 48a can then be returned to the neutral position by moving it against the shoulder 77 to pivot the bar 71 back to the selector locking position shown in FIG. 4 so that both of the voting keys 48a and 48b are restored to their neutral positions.

While a particular embodiment of the invention has been illustrated and described, it will be apparent that many modifications will readily occur to those skilled in this art and it is, therefore, contemplated by the appended claims to cover any such modifications as fall within the true spirit and scope of the invention.

What is claimed as new and desired to be secured by Letters Patent of the United States is:

1. In a voting machine of the type employing first and second selectors each mounted for sliding movement along at least one column from a neutral position to at least one selecting position indicating the voter's choice, the improvement which comprises means interlocking the first and second selectors for recall voting, said interlocking means including structure for positively engaging said second selector to prevent its sliding movement from its neutral position, said interlocking means including structure engaged by said first selector when the latter is moved to a selecting position for rendering said interlocking means effective to release said second selector for sliding movement to a selecting position, and said interlocking means further including means engaging said first selector for preventing return sliding movement of said first selector to its neutral position after the second selector has been moved to a selecting position.
2. In a voting machine of the type employing first and second selectors each mounted for sliding movement along at least one column from a neutral position to at least one selecting position indicating the voter's choice, the improvement which comprises means interlocking the first and second selectors for recall voting, said interlocking means including structure for positively engaging said second selector to prevent movement of the second selector from its neutral position, said interlocking means including structure engaged by said first selector when the latter is moved to a selecting position for rendering said interlocking means effective to release said second selector for sliding movement to a selecting position.
3. Apparatus as defined in claim 1 wherein said interlocking means includes structure pivotally mounted on and extending along a portion of said column.
4. Apparatus as defined in claim 2 wherein said interlocking means includes structure pivotally mounted on and extending along a portion of said column.
5. In a voting machine of the type employing first and second selectors both mounted for sliding movement along a single column carrying a plurality of spaced apart stops each of said selectors being movable from a neutral position adjacent one of said stops to at least one selecting position indicating the voter's choice, the movement of each selector being limited by said stops, the improvement which comprises means interlocking the first and second selectors for recall voting, said interlocking means including a bar extending along the column to span the space between the two stops against which the selectors rest when in their neutral positions, said bar including means for positively engaging said second selector to prevent its sliding movement from its neutral position, said bar including structure engaged by said first selector when the latter is moved to a selecting position for rendering said bar effective to release said second selector for sliding movement to a selecting position, and said bar further including means engaging said first selector for preventing return sliding movement of said first selector to its neutral position after the second selector has been moved to a selecting position.
6. In a voting machine of the type employing first and second selectors both mounted for sliding movement along a single column carrying a plurality of spaced apart stops each of said selectors being movable from a neutral position adjacent one of said stops to at least one selecting position indicating the voter's choice, the movement of each selector being limited by said stops, the improvement which comprises means interlocking the first and second selectors for recall voting, said interlocking means including a bar extending along the column to span the space between the two stops against which the selectors rest when in their neutral positions, said bar including means for positively engaging said second selector to prevent movement of the second selector from its neutral

position, said bar including structure engaged by said first selector when the latter is moved to a selecting position for rendering said bar effective to release said second selector for sliding movement to a selecting position.

7. In a voting machine of the type employing first and second selectors each manually slideable along a column containing a plurality of spaced apart stops, each selector being movable from a neutral position adjacent one of said stops to at least one selecting position, the improvement which comprises a bar mounted for pivotal movement from a first selector locking position to a second selector releasing position, said bar including a first selector engaging portion in engagement with the first selector when the latter is in neutral position and when the bar is in its selector locking position, said second portion cooperating with one of the stops to prevent movement of said second selector from its neutral position as long as the first portion is in engagement with the first selector, said bar being recessed adjacent said first portion to permit manual sliding movement of the first selector from its neutral position along the column and out of engagement with the bar so that the bar is free to pivot, a first cam surface on said bar engaged by the second selector when the latter is moved from its neutral position for pivoting the bar upon the column to the selector releasing position, and said bar having a second surface thereon engaged by the second selector when the latter is moved to a selecting position for preventing return of the bar to its selector locking position, thereby preventing return movement of the first selector back to its neutral position after the second selector has been moved to a selecting position.

8. The apparatus defined by claim 7 wherein means are provided for pivotally mounting the bar at different spaced apart positions along the column to permit different pairs of selectors to be interlocked as desired in programming the voting machine for an election.

9. In a voting machine of the type employing first and second selectors each manually slideable along a column containing a plurality of spaced apart stops, each selector being movable from a neutral position adjacent one of said stops to at least one selecting position, the improvement which comprises a bar mounted for pivotal movement from a first selector locking position to a second selector releasing position, said bar including a first selector engaging portion in engagement with the first selector when the latter is in neutral position and when the bar is in its selector locking position, said bar further including a second selector engaging portion in engagement with the second selector when the latter is in neutral position and when the bar is in its selector locking position, and said second portion cooperating with one of the stops to prevent movement of said second selector from its neutral position as long as the first portion is in engagement with the first selector.

10. The apparatus defined by claim 9 wherein means are provided for pivotally mounting the bar at different spaced apart positions along the column to permit different pairs of selectors to be interlocked as desired in programming the voting machine for an election.

11. In a voting machine of the type employing first and second selectors each manually slideable along a column containing a plurality of spaced apart stops, each selector being movable from a neutral position adjacent one of said stops to at least one selecting position, the improvement which comprises a bar mounted for pivotal movement from a first selector locking position to a second selector releasing position, said bar including a first selector engaging portion in engagement with the first selector when the latter is in neutral position and when the bar is in its selector locking position, said bar further including a second selector engaging portion in engagement with the second selector when the latter is in neutral position and when the bar is in its selector locking position, said bar being recessed adjacent said first portion to permit manual sliding movement of the first selector from its neutral position along the column and out of engagement with the bar so that the bar is free to pivot, a first cam surface on said bar engaged by the second selector when the latter is moved from its neutral position for pivoting the bar upon the column to the selector releasing position, and said bar having a second surface thereon engaged by the second selector when the latter is moved to a selecting position for preventing return of the bar to its selector locking position, thereby preventing return movement of the first selector back to its neutral position after the second selector has been moved to a selecting position.

10 with the second selector when the latter is in neutral position and when the bar is in its selector locking position, said second portion cooperating with one of the stops to prevent movement of said second selector from its neutral position as long as the first portion is in engagement with the first selector, said bar being constructed and arranged to permit manual sliding movement of the first selector from its neutral position along the column and out of engagement with the bar to free the bar for pivoting, and a cam surface on said bar engaged by the second selector when the latter is moved from its neutral position for pivoting the bar upon the column to the selector releasing position.

15 12. The apparatus defined by claim 11 wherein means are provided for pivotally mounting the bar at different spaced apart positions along the column to permit different pairs of selectors to be interlocked as desired in programming the voting machine for an election.

20 13. In a voting machine of the type employing first and second selectors each manually slideable along a column containing a plurality of spaced apart stops, each selector being movable from a neutral position adjacent one of said stops to at least one selecting position, the improvement which comprises a bar mounted for pivotal movement from a first selector locking position to a second selector releasing position, said bar further including a selector engaging portion in engagement with the second selector when the latter is in neutral position and when the bar is in its selector locking position, said portion cooperating with one of the stops to prevent movement of said second selector from its neutral position as long as the first portion is in engagement with the first selector, said bar being constructed and arranged to permit manual sliding movement of the first selector from its neutral position along the column and out of engagement with the bar to free the latter for pivoting, a first surface on said bar engaged by the second selector when the latter is moved from its neutral position for pivoting the bar upon the column to the selector releasing position, said bar having a second surface thereon engaged by the second selector when the latter is moved to a selecting position for preventing return of the bar to its selector locking position, thereby preventing return movement of the first selector back to its neutral position after the second selector has been moved to a selecting position.

25 14. The apparatus defined by claim 13 wherein means are provided for pivotally mounting the bar at different spaced apart positions along the column to permit different pairs of selectors to be interlocked as desired in programming the voting machine for an election.

30 15. In a voting machine of the type employing first and second selectors each manually slideable along a column containing a plurality of spaced apart stops, each selector being movable from a neutral position adjacent one of said stops to at least one selecting position, the improvement which comprises a bar mounted for pivotal movement from a first selector locking position to a second selector releasing position, said bar including a selector engaging portion in engagement with the second selector when the latter is in neutral position and when the bar is in its selector locking position, said portion cooperating with one of the stops to prevent movement of said second selector from its neutral position as long as the first portion is in engagement with the first selector, said bar being constructed and arranged to permit manual sliding movement of the first selector from its neutral position along the column and out of engagement with the bar to free the bar for pivoting, and a cam surface on said bar engaged by the second selector when the latter is moved from its neutral position for pivoting the bar upon the column to the selector releasing position.

35 16. The apparatus defined by claim 15 wherein means are provided for pivotally mounting the bar at different spaced apart positions along the column to permit different pairs of selectors to be interlocked as desired in programming the voting machine for an election.

17. In a voting machine of the type employing first and second selectors each manually slideable along a column from a neutral position adjacent one of said stops to at least one selecting position, the improvement which comprises a bar mounted for pivotal movement from a first selector locking position to a second selector releasing position, said bar including a selector engaging portion in engagement with the second selector when the latter is in neutral position and when the bar is in its selector locking position to prevent movement of said second selector from its neutral position, said bar including means cooperating with the first selector when the latter is in its neutral position to prevent the bar from pivoting to its selector releasing position, said bar being constructed and arranged to permit manual sliding movement of the first selector from its neutral position along the column to free the bar for pivoting, a first surface on said bar engaged by the second selector when the latter is manually moved from its neutral position for pivoting the bar upon the column to the selector releasing position, said bar having a second surface thereon engaged by the second selector when the latter is moved to a selecting position for preventing return of the bar to its selector locking position, thereby preventing return movement of the first selector back to its neutral position after the second selector has been moved to a selecting position.

18. The apparatus defined by claim 17 wherein means are provided for pivotally mounting the bar at different spaced apart positions along the column to permit different pairs of selectors to be interlocked as desired in programming the voting machine for an election.

19. A voting machine comprising at least one column defining a plurality of neutral spaces and a plurality of selecting spaces for indicating the voter's choice, first and second selectors slidably mounted on said column, each being slidably movable from a neutral space to one of the plurality of selecting spaces to indicate the voter's selection, and means interlocking the first and second selectors for recall voting, said means defining structure for positively engaging said second selector to prevent its sliding movement from its neutral space until the first selector is slidably moved to a selecting space.

20. A voting machine comprising at least one column defining a plurality of neutral spaces and a plurality of selecting spaces for indicating the voter's choice, first and second selectors slidably mounted on said column, each being slidably movable from a neutral space to one of the plurality of selecting spaces to indicate the voter's selection, and means interlocking the first and second selectors for recall voting, said means defining structure for positively engaging said second selector to prevent its sliding movement from its neutral space until the first selector is slidably moved to a selecting space, said means including structure for positively preventing return sliding movement of the first selector to its neutral space after the second selector has been moved to a selecting space.

21. A voting machine comprising at least one column defining a pair of neutral spaces and at least one selecting space adjacent each neutral space for indicating the voter's selection, first and second selectors slidably mounted on said column, each being slidably movable from a neutral space to a selecting space indicating the voter's choice, and means interlocking the first and second selectors for

recall voting, said means defining structure for positively preventing sliding movement of the second selector from its neutral space until the first selector is slidably moved to a selecting space.

5 22. A voting machine comprising at least one column defining a pair of neutral spaces and at least one selecting space adjacent each neutral space for indicating the voter's selection, first and second selectors slidably mounted on said column, each being slidably movable from a neutral space to a selecting space indicating the voter's choice, and means interlocking the first and second selectors for recall voting, said means defining structure for positively preventing sliding movement of the second selector from its neutral space until the first selector is slidably moved to a selecting space, said means including structure for positively preventing sliding return movement of the first selector to its neutral space after the second selector has been slidably moved to a selecting space.

20 23. A voting machine, comprising at least one column defining a pair of neutral spaces and at least one selecting space adjacent each neutral space for indicating the voter's selection, first and second selector means slidably mounted on said column, each being slidably movable from a neutral space to a selecting space to indicate the voter's choice, a plurality of stop means selectively positioned in spaced relation along said column for limiting the sliding movement of said selectors, said stop means being positioned adjacent one side of each selector when the selectors are in neutral spaces, means interlocking the first and second selectors for recall voting, said means including a bar pivotally mounted on said column and extending along said column to span at least two of said stop means, said bar including means for positively engaging said second selector to prevent its sliding movement from its neutral space unless said first selector has been slidably moved to a selecting space, and said bar including means for preventing the sliding return movement of said first selector to its neutral space if the second selector is in a selecting space.

40 24. A voting machine, comprising at least one column defining a pair of neutral spaces and at least one selecting space adjacent each neutral space for indicating the voter's selection, first and second selector means slidably mounted on said column, each being slidably movable from a neutral space to a selecting space to indicate the voter's choice, a plurality of stop means selectively positioned in spaced relation along said column for limiting the sliding movement of said selectors, said stop means being positioned adjacent one side of each selector when the selectors are in neutral spaces, means interlocking first and second selectors for recall voting, said means including a bar pivotally mounted on said column and extending along said column to span at least two of said stop means, said bar including means for preventing the sliding movement of said second selector from its neutral space unless said first selector has been slidably moved to a selecting space.
